UNITED STATES PATENT OFFICE.

JAMES J. WOOD, OF BROOKLYN, ASSIGNOR, BY MESNE ASSIGNMENTS, TO
THE FULLER ELECTRICAL COMPANY, OF NEW YORK, N. Y.

MAGNETO-ELECTRIC MACHINE.

SPECIFICATION forming part of Letters Patent No. 243,747, dated July 5, 1881.

Application filed August 16, 1879.

To all whom it may concern:

Be it known that I, JAMES J. WOOD, of Brooklyn, Kings county, New York, have invented certain new and useful Improvements 5 in Magneto-Electric Machines, of which the following is a specification.

The main improvement which my invention aims to effect in magneto-electric or dynamo-electric machines is to provide such a construction and arrangement of the stationary or inducing magnets and of the armature-bobbins relatively to each other that the magnets shall not oppose but mutually complement and strengthen each other and present an intense 15 or concentrated magnetic field for the armature to sweep through; such an arrangement, also, as will effect the rapid and certain magnetization and demagnetization of the armature-bobbins, concentrating and confining this magnetic action on the bobbins themselves, thus avoiding the useless magnetic excitation and consequent electrical and mechanical loss in those parts of the machine which give no return in the current, and hence enabling the objectionable heating effect and wasted magnetism common to most existing machines to be 20 obviated and a greater current to be produced with less power.

In addition to the main improvement here 25 indicated, my invention also aims to improve the mechanical structure of the machine in its several details.

To these ends my invention embodies a number of novel features, all of which are herein- 30 after fully set forth, and each novel feature definitely expressed in the claims.

Figure 1 of the annexed drawings presents a side elevation of my improved machine, and Fig. 2 a plan view thereof, shown partly in section at the commutator end. Fig. 3 is a sectional elevation on line $\alpha\alpha$ of Fig. 1, looking in the direction of the arrow, showing the arrangement of magnets on the end frame. Fig. 4 is an end elevation of the machine viewed from the commutator end. Fig. 5 is an end elevation of the armature removed and viewed from the same end. Figs. 6, 7, and 8 show, respectively, an end elevation, side elevation, and longitudinal section of one of the armature-bob-

bin cores, and Fig. 9 shows most of the parts 50 of the commutator separated.

In general form the machine consists of a base, A, from either end of which end frames, B B', rise, between which the revolving armature C g is mounted. The end frames or standards, B B', are formed with short feet or lugs a a', by which the frames are bolted to the base, and they are rigidly held at the proper distance apart by stay-rods b b arranged at suitable intervals, as shown. It will be observed 60 that the frames B B' are of substantially ring shape, as seen best in Figs. 3 and 4, which presents practical advantages hereinafter explained, and from the bottom of the central openings in the frames short arms rise and terminate in central hubs, c c, which form the bearings in which the ends of the armature-shaft D are journaled, as seen in Figs. 1, 2, 3, and 4. On one end of the armature-shaft is fixed the pulley d, by which power is applied 70 to rapidly rotate the armature as usual in machines of this class, while the opposite end of the shaft receives the commutator, as shown, the springs of which extend from parallel arms f f' projecting from a plate, e, fixed on the neck 75 of the hub c, as seen in Figs. 1 and 2.

N S indicate the stationary or inducing magnets of the machine, which are mounted on the inner side of the frames B B' on each side of the armature, as illustrated in Figs. 1, 2, and 3. 80 These magnets, as will be readily understood, may be permanent magnets or electro-magnets, and, if electro-magnets, may be magnetized by an electric current from a source independent of the machine, or may be magnetized by the 85 current from the machine itself, on the well-known principle of mutual accumulative action or reaction now generally adopted in machines of this class. As the latter plan is, of course, what I prefer to adopt, as illustrated 90 in the drawings, I also prefer to form the cores of these magnets by casting them solidly on and continuous with the end frames, B B', as shown in section in Fig. 2.

It will also be now observed that the stationary magnets are arranged in a circle upon the ring-shaped frames at equal intervals, and project therefrom parallel with each other and

with the axis of the armature, and are so wound, as illustrated, that opposite poles succeed each other in each series, as seen best in Fig. 3, while opposite poles face each other in 5 the opposite series on either side of the armature, as seen best in Figs. 1 and 2. Hence by this arrangement the inductive action of the several magnets on each other tends but to strengthen and mutually assist each other, 10 thus avoiding all mutual counter-action such as largely exists where similar poles succeed or face each other, as in most existing machines, and at the same time producing by this arrangement an intense magnetic field in 15 the narrow space between the opposite poles of the two series in which the armature revolves. Now, as the poles of the field-magnet are of even multiple number and of alternate polarity and are all cast in one piece, springing 20 without joint or division from a common base or neutral section which extends in direct succession from pole to pole, each pole is thus in actual molecular connection with its neutral section, each set of poles has a distinct 25 neutral section, and each pole and set of poles directly complements and strengthens the others, thus forming what may be called an undivided multiple magnet in distinction from a common bipolar magnet or from a divided 30 multipolar magnet, the peculiar advantage of which is that all the magnetism becomes concentrated at the very extremities of the poles, thus forming a most intense magnetic field, which becomes concentrated solely upon and 35 utilized by the armature. Hence this construction provides a very effective field-magnet, as it possesses no magnetism except where it is of service, and there it is intensified, whereas when a magnet is made in a number of 40 pieces bolted to their central section magnetism exists at each joint, so as to cause a diffusion or waste instead of a concentration and economy of magnetism.

To produce the improved result above described it is, of course, necessary that the field-magnets have an even multiple number of poles, that they be formed in one homogeneous piece, that the poles spring from a common neutral section extending in direct succession from pole to pole, or in a circular range, and that all the poles be magnetized simultaneously with alternate complementary polarities. Hence a star-shaped frame with a north and south pole on each ray distinct from every 55 other ray, or a cylinder cast with an odd number of poles projecting inward, a portion only of which are magnetized simultaneously, as has been heretofore employed, although cast in one piece, does not satisfy the above conditions, has 60 not the multiple complementary character of my field-magnet, and cannot produce the result stated. Now, the armature consists of a disk or light wheel, C, fixed at its center to the rotary shaft D, and carrying near its periphery 65 a series of induction coils or bobbins, g. These bobbins are each wound on an iron core, g', and are double, or have a north and south pole at

opposite ends when magnetized, and it will be seen that these bobbins are arranged near the periphery of the armature-disk parallel 70 with its axis and parallel with the stationary magnets, or in the same relative arrangement with said magnets, so that their two polar extremities are thus arranged to sweep closely past the extreme polar faces of the stationary 75 magnets. Hence, when the armature revolves, the opposite and extreme ends of its double-poled bobbins pass directly over the extreme polar ends of the two opposite magnet or magnetic poles, N S, thus bringing the strongest 80 possible magnetic influence on each bobbin, causing the cores to magnetize from each end simultaneously with complementary polarities, thus answering the rapid, complete, and harmonious magnetization of the cores and the development of a certain and energetic current 85 in its coils. Hence, by this arrangement, a powerful electric current is produced, while little or no heating effect is noticeable on account, it is believed, that by this arrangement the 90 magnetic action is concentrated in a harmonious manner upon the parts directly concerned in producing the current and discordant effects, and useless magnetic excitation thus entirely avoided. 95

In order to obtain a still better effect from the described relative arrangement of magnets and bobbins, I prefer to construct the armature-disk e holding the bobbin of a non-magnetic material, preferably of brass, so that the 100 non-electrical part of the armature is thus rendered non-magnetic or entirely neutral to magnetic influence. Hence no useless magnetic excitation is produced in it, but all the magnetic action is concentrated on the magnets and bobbins which alone are concerned in producing the current, thus largely avoiding both the heating of the armature and loss of power.

To further render the magnetic construction of the machine more effective, another feature 110 of my invention consists in constructing both the stationary magnets and their cores and the armature bobbins and cores in the form of truncated sectors of a circle, as shown fully in Fig. 3, their side lines or boundaries being radial 115 to the center of the armature, by which it will be seen that the armature-bobbins enter and leave the magnetic field full-sided and abrupt, insuring a rapid and complete magnetization and demagnetization of the cores. To further 120 contribute to this effect, I prefer to adopt the approved plan of forming the cores of the bobbins hollow and slitting them lengthwise, as shown fully in Figs. 5, 6, and 7; and I also prefer to form the polar faces of the stationary 125 magnets sufficiently broad to cover two bobbins at a time, but they may be broader or narrower than this.

I prefer to arrange a series of bridges or bars of brass, v, between the poles of the several 130 magnets, as shown in Fig. 5, which thus serve to brace the magnets together and prevent the vibration of their polar ends, and consequently the noisy hum produced thereby, thus causing

the machine to run practically silent. These bridges, as shown, are of wedging form, and are driven in with a wedging action in the tapering space between the segmental magnet-poles, thus enabling the poles to be tightly braced together, while the bars are securely retained in position between them, but may, if required, be permanently fastened to the poles by small screws, as illustrated.

10 It will be observed that the group of stationary magnets on the end frames on each side of the armature are preferably six in number, arranged equally distant around the ring-shaped frame, as seen best in Fig. 3, but their number may be more or less. It will now be readily understood that this ring form of frame has the advantage of disposing the metal of the frame uniformly in relation to the circular group of magnets, thus obtaining a much 20 more harmonious magnetic arrangement and effect than where the form of the frame is irregular and the metal disposed irregularly around the several magnets. Furthermore, it will be seen that while the rotary armature 25 acts as a fan to discharge the air from its periphery by centrifugal force, the outer or ring portion of the frame is imperforate and of a width to cover the groups of magnets and also the outer portion of the armature with its 30 groups of bobbins, so as to prevent the discharge of this air laterally and compel it to always discharge centrifugally through and from the radial spaces between the magnets of the frame and the bobbins of the armature, 35 while the central opening in the frame which comes within the circle of magnets and bobbins admits a central inflow of air to the armature to keep up the centrifugal discharge of the same from the armature, thereby insuring 40 a constant radial circulation of air through the machine, which cools down any parts that may by any chance tend to become heated, thus presenting a material advantage over a centrally-closed end frame or a frame perforated 45 at its periphery, as commonly employed.

The bobbins in the armature are preferably of much greater number than the magnets or in a multiple series relatively to the number of the stationary magnets and arranged in 50 distinct groups, each group having the same number of bobbins as there are stationary magnets. Thus, as shown in Fig. 5, I prefer to construct the armature for three groups of six bobbins each, only one of which is shown 55 in position for sake of clearness. Each bobbin g of the group is wound, as shown in Fig. 5, and all are joined together in connected series, the terminal wires only of the group being brought to the commutator, illustrated in 60 Figs. 2 and 5, which is both a simple and advantageous arrangement. Each of the three groups is wound in the same way as the one group illustrated, and its terminal wires brought to a distinct section in the commutator, 65 tor. Hence, as the machine is adapted for three groups of bobbins, there are accordingly three sections in the commutator corresponding

thereto, as illustrated, and as the bobbins of each group are connected together for intensity, the currents from the three groups combine simultaneously through the commutator-springs $h' h^2 h^3$ for quantity, thus providing both an intense and strong current, well adapted for producing electric light, for plating, or other uses.

75 It will now be readily understood that as the group of bobbins is revolved past the magnets an alternating current will be produced through the whole group as the bobbins successively pass each magnet, thus producing 80 six alternately positive and negative impulses during one revolution. The section of the commutator to which this group connects is therefore formed with six segments, on which the commutator-springs $h' h^2 h^3$ successively bear 85 at diametrically-opposite sides, as shown best in Figs. 2 and 5, and which thus serve simply as pole-changes to turn these impulses into one current of uniform direction.

90 It will be seen that the commutator which I prefer to employ is of that kind which is composed of laterally-segmented intermeshing disks, as shown in Figs. 2, 5, and 9. Each section of the commutator consists of two of these disks, $k' k^2$, insulated from each other by 95 the inner washer, i' , and insulated from the armature-shaft by the rubber sleeve l , and separated from the other sections by the outer insulating-washers, $l' l^2$, &c. The two disks $k' k^2$ of one section have each three equidistant 100 lateral segments, which intermesh alternately with those of the other disk, as will be fully understood from Figs. 2, 5, and 9, and are slightly separated from each other at their radial edges corresponding to the neutral 105 points in the rotation of the armature, while one of the terminal wires of the armature is connected to one of the disks and the other terminal wire to the other disk, as shown in 11 Figs. 2 and 5. It will now be readily understood, on reference to Fig. 5, that as each sixth of a revolution reverses the segments of the commutator with relation to the springs $h' h^2 h^3$, and as the current produced in the armature-bobbin is also simultaneously reversed during 11 this movement relatively to what it was at the previous sixth, hence the alternating currents are always made to flow in the same direction from the springs $h' h^2 h^3$, the negative currents always going to one spring and the positive to 12 the other, thus producing a continuous current. The circuit-wires of the machine therefore extend from the spring-rods $f f'$ of the armature, which are, of course, insulated from each other on the plate e , and descend therefrom through the base of the machine, where the wire u connects beneath the base directly with the binding-screw l , while the other wire connects to one end of the coils of one group of stationary magnets, while the other end of 13 the coils connects beneath the base with the other binding-screw, t , as shown by dotted lines in Fig. 2; hence a conductor joining the binding-screws closes the circuit of the machine.

It will now be observed that the arrangement of connections between the groups of bobbins and the magnet-coils is such that the currents from the several distinct groups of 5 bobbins are confined into one common current, and this combined current sent in its entirety through the coils of the inducing-magnet before being delivered from the terminals of the machine, which arrangement is found to produce 10 a greatly improved result. It has, of course, been common in machines where all the bobbins are coupled in a continuous connected series to send the entire current through the magnet-coils, as the current could, of course, not be divided under this arrangement of the bobbins; but in machines where the bobbins are arranged in distinct multiple groups they have been thus divided into groups for the express object of connecting one group with the 15 magnet-coils and delivering the current of the other group or groups from the terminals of the machine for the uses to which the machine may be applied. I have found, however, that when the currents of the different groups 20 are combined and the whole of this united current circulated through the magnet-coils in its passage from the machine, instead of a loss occurring a machine of greatly improved character is produced, so that, for instance, 25 the light obtainable from the machine with the same horse-power is of about twice the candle-power that would be obtained were the connections made in the usual manner, and which have heretofore been thought essential for the 30 best effect.

The wires from the armature pass to the commutator through grooves in the shaft D, as usual, which grooves are covered by the sleeve m, fixed permanently over the same and 35 serving as the journal for that end of the shaft in the bearing e. A minor feature of my invention consists in forming a raised bead or ring, n, on the inner end of the bearing, as shown in Fig. 2, thus forming a guard which 40 prevents the oil-drip from the bearing entering the wire grooves, and thus tending to rot the insulating covering thereon.

The mode of fastening the wires in the commutator sections and insulating their ends from 45 the succeeding sections will be understood from Figs. 2 and 9. In Fig. 2 the first section of the commutator corresponding to the one group of bobbins in the armature is shown in section, the other two divisions of the commutator being removed as unnecessary for illustration. In Fig. 9 all the parts of two sections of the commutator are shown separated and spread apart in true relative position on the same horizontal line joining their center. Now, if 50 there be three groups of bobbins in the armature, there will hence be six terminal wires. Three wires pass, as seen in Fig. 2, from the ends of the grooves in the shaft over the rubber sleeve l (which passes through all the commutators) into and through the several pieces of the commutator, the several wires terminating successively in the disks of the commu-

tator in the order of their outer extension therein, as will be readily understood from Figs. 2, 5, and 9. Thus the first outer insulating-washer, l', Fig. 9, has six free holes to admit all the wires. One of the wires, however, terminates and is fastened in a tight hole in the first disk, k', and the other five pass through the five free holes therein. The other terminal wire from the same group as the first wire is next fastened in a tight hole in the second disk, k'', and the remaining four wires from the other two groups pass through the four free holes therein, and terminate in the same manner and same successive order in the other successive disks of the commutator, as will be readily understood. Now, the internal insulating-washers i', i'', &c., between the disks k', k'', &c., are also formed with free holes to admit the passage of all the wires terminating in advance of that washer, but are imperforate at the point corresponding to the wire terminating in the preceding disk, as shown in Fig. 9, and hence effectively prevent the ends 80 of the preceding wires extending through and making contact with the succeeding disks, thus obviating the possibility of the machine becoming short-circuited within itself. The terminal wires are each fastened in their appropriate disks by the small studs or screws o, (shown in Fig. 9,) which have heads slightly eccentric or reduced on one side, and are arranged close to and slightly intersecting the periphery of the tight holes in which the ends 85 of the wires are inserted, as illustrated. It will hence be seen that when the screw is turned slightly out, so that the enlarged part of the head recedes from the hole, the end of the wire may be readily inserted therein, when, by tightening up the screw, the enlarged part of the head approaches the hole and thus firmly clamps the wire therein. This device, as will 90 be seen, forms a neat, simple, and effective fastening, and has the advantages that it is 95 small and yet secure, and lies flush with the inner face of the disk.

The special construction of the armature-bobbin cores and the manner of mounting and securing them in the armature-disk are illustrated in detail in Figs. 5, 6, 7, and 8. The cores g', as shown, while being of segmental shape, hollow, and slit lengthwise, are also formed with a transverse hole, r, extending obliquely through the middle of the same from one side to the other, as seen in section in Fig. 8 and in dotted lines in Figs. 6 and 7. The wire to form the coils of the bobbins is passed through this hole till the middle of the necessary length of wire is reached, when its opposite ends are coiled around either end of the core, as will readily be understood. It will thus be seen that by this device the two end coils or bobbins of the core are connected directly through the center of the core, thus 100 avoiding a splice or coupling in the middle of the bobbin or core, and hence securing the advantages of neatness, compactness, and certainty of connection, as well as simplicity and 105

cheapness of construction. The core is also formed with two flanges on either end, between which the coil-wire is wound, while the middle of the core between the two central flanges, is formed to serve as a tenon, *q*, and the core thus shaped is formed of fine cast-iron in one continuous casting, which is subsequently annealed to great softness. Now, the armature-disk is formed with a series of corresponding peripheral sockets or mortises, *p p*, in which the middle portion or tenon of the cores is tightly socketed, with the flanges thereof embracing the sides of the disks, as shown in Figs. 1, 2, and 5, while the cores are held securely there-in by three curved sections, *s*, preferably made of non-magnetic metal, screwed to the periphery of the disk, one of which is represented as loosened in Fig. 5. This construction of the armature is both simple and secure, and admits of the cores or bobbins being readily put in place or removed when required, and enables them to be held with firmness and exactitude. It has also the further advantage that the neutral middle or tenon portion only of the cores is inclosed in the armature-disk, while the bobbins or main portions project free and exposed to the air on either side thereof, thus allowing any heat that may develop in these parts to quickly radiate, which is not the case where the bobbins are socketed and inclosed bodily in the disk.

It will be observed from Figs. 5 and 7 that the sides of the mortises in the armature-disk as well as of the tenons in the armature-cores are recessed, which, as will be understood, reduces the surface necessary to be finished in order to properly fit the parts together, and hence requires less work thereon.

It will now be observed that in all the mechanical features of the machine I aim to secure compactness and simplicity as well as efficiency and cheapness of construction, while in the electric and magnetic features of the machine I aim to secure concentrated action, together with quickness and certainty, and to harmonize all parts into mutual assistance, thus providing a machine which does not heat appreciably, and furnishes a greater current for the same amount of power.

The main features of my invention are, of course, specially designed and adapted for magneto-electric machines or those which generate an electric current; but it will be obvious that some of these features may also be applicable to electro-magnetic machines or those which utilize an electric current.

I am aware that it is not new to cast the cores of magnets in one piece with a sustaining-ring; that armature-bobbins of a magneto-electric machine have been made in the form of truncated sectors of a circle in cross-section with the field-magnets of other shape; that the ends of cores of a magneto-electric machine have been made in the form of truncated sectors, and that single electro-magnet cores have been made solid with the end flanges, and I

therefore lay no claim to either of these constructions.

The features which I claim as my invention are as follows:

1. The combination, with the rotary armature *C g*, of the shaft *D*, having its journal, and through which the wires pass, provided with a sleeve, *m*, having a raised encircling-bead, *n*, substantially as and for the purpose set forth. 75

2. A commutator disk or section constructed with a perforation to receive the armature terminal wire, in combination with the eccentric stud *o*, sunk in the said disk, with its periphery arranged close to and slightly intersecting the periphery of the said perforation, substantially as and for the purpose set forth. 80

3. The combination, with a commutator, substantially such as described, of the internally-separating and insulating washers *i*, *l*, &c., 85 arranged between the several sections and perforated to admit the passage of wires terminating in succeeding sections, but imperforate at the wire terminating in the preceding section, substantially as and for the purpose set forth. 90

4. The double bobbin core or cores *g'*, formed with a central communicating-hole, *r*, substantially as and for the purpose set forth.

5. The combination, in a magneto-electric or 95 equivalent machine, of a rotating armature-disk provided with a series of peripheral mortises or sockets, in combination with a corresponding series of bobbins, each having a portion formed as a tenon to fit in the said sockets, 100 leaving coiled portions free, substantially as shown and described.

6. The combination of a rotary armature-disk formed with a series of peripheral mortises or sockets, with a corresponding series 105 of bobbins each having a portion formed as a tenon to fit in said sockets and coiled portions projecting free from the armature-disk, together with a rigid sectional ring, *s s*, arranged to fix the tenoned portions of the said bobbins in 110 the said sockets, substantially as herein shown and described.

7. The combination, with the segmental magnets *N S*, of the non-magneto wedging brace-bars *u*, driven in between the converging polar edges thereof, substantially as and for the purpose set forth. 115

8. The bobbin-cores *g'*, constructed with a tenon, *q*, on a portion of their length, with projecting flanges on either side thereof adapted 120 to socket in a mortised armature plate or disk, with the flanges embracing the sides thereof, substantially as herein shown and described.

9. A double magneto-electric bobbin-core, *g'*, formed with projecting flanges in one continuous casting, and provided with a central shank between the cores, substantially as shown and described. 125
